UNITED STATES PATENT OFFICE.

CARL RYDELL, OF MANILA, PHILIPPINE ISLANDS.

LIFE-SAVING APPARATUS.

1,201,877.

Specification of Letters Patent. Patented Oct. 17, 1916.

Application filed July 3, 1915. Serial No. 37,906.

To all whom it may concern:

Be it known that I, CARL RYDELL, a citizen of the United States, residing at Manila, in the Province of Luzon, Philippine Islands, 5 have invented new and useful Improvements in Life-Saving Apparatus, of which the following is a specification.

This invention relates to life saving apparatus and more particularly to the construction of the boats and davits employed upon 10 sea-going vessels.

One of the principal objects of the invention is the provision of an apparatus of this type in which a novel form of boat group 15 and a novel form of davit construction is utilized whereby the boats may be conveniently lowered one by one from each group and rapidly loaded without danger to the passengers.

20 Another object of the invention is the provision of a novel form of davit construction for lowering the types of boats herein described and which is so constructed and its parts so arranged that a relatively small 25 amount of deck space is occupied and at the same time a sufficient overhang of the hull is provided in lowering.

Further objects of the invention will appear as the following specific description is 30 read in connection with the accompanying drawings which form a part of this application, and in which:—

Figure 1 is a side elevation showing the 35 position of two boat groups with a single davit construction between them. Fig. 2 is a vertical sectional view through the ship showing the davit construction in rear elevation. Fig. 3 is a side elevation of the davit construction showing one of the davit 40 arms in raised position and the opposite davit arm in lowered position. Fig. 4 is a horizontal view taken on the line 4—4 of Fig. 3. Fig. 5 is a perspective view of one of the boat groups. Fig. 6 is a perspective view 45 of a lashing used when lowering the boats to prevent the same from swinging toward and away from the ship in a heavy sea. Fig. 7 is a perspective view of one of the hook blocks.

50 Before proceeding to describe the davit construction, I shall describe briefly the construction of the boats which differ essentially from the construction shown in my pending application Serial No. 759,716. In 55 that construction the air tanks at the end of the boats were made removable as an en-

tirety and were placed in the top boat so that they could be removed and attached to the lower boats of the group as these boats were made up for loading and lowering. In the 60 present instance the top boat is complete in itself and is ready for immediate lowering and while this boat is being loaded and lowered the second boat of the group may be 65 properly made up. During the loading and lowering of the second boat the third boat of the group is made up. While the top boat of the group is made complete in itself, and normally remains in such condition, it is 70 constructed in a similar manner to the other boats of the group, but the remaining lower boats have the bulk heads and top plates forming their air tanks disconnected for providing room whereby the upper boats may 75 be nested therein.

Each of the boats of the group comprise a hull 1, in which suitable thwarts are placed and adjacent each end the hull is provided on its inner sides with suitably packed guide-ways, not shown, which receive bulk heads 3. 80 These bulk heads together with the deck plates 4 form air tanks which provide the necessary buoyancy and make the boat substantially unsinkable. To prevent capsizing of the boat there is preferably provided as 85 in the former application suitable air tanks 6 which extend longitudinally of the boat as shown, and which are so placed as not to interfere with the nesting. Each boat is provided with reinforcing joints 7 which extend 90 beneath the hull and terminate above the gunwale where they are connected by cross rods 8 having eyes 9 formed therein for receiving the hooks of the lowering tackle 95 as will be hereinafter described. The bulk heads, deck plates and other suitable paraphernalia, such as thwarts and so forth of the lower boats are packed in the bottom of each boat and serve as a support for the keel 100 of the next superimposed boat. If desirable, these boats may have a cover such as shown in the application formerly mentioned, and may also be supplied with a sea anchor as is disclosed in such application if desired.

It will be understood that each davit construction embodies independent lowering arms, one of the arms relating to a group upon one side of the davit construction and the other arm relating to the group on the opposite side of the davit construction. The 110 opposite end of the first group referred to is taken care of by another davit construc-

tion, say to the right, while the opposite end of the last group referred to is taken care of by another davit construction to the left. Each davit construction consists of 5 two pairs of triangular frames 10 and 11, the members of each pair being connected together at their rear edges by diagonally arranged reinforcing strips or bars 12 and which are open at their front to permit of 10 the passage of the davit arms as will be readily understood. The pairs of frames are connected together by a bridge piece 13 and pivotally mounted between each pair is a 15 davit arm 14 which carries a pair of substantially triangular braces 15 and 16 arranged upon the front and rear thereof.

Each davit arm has journaled in its outer end a suitable pulley 17 over which passes the lowering cable 18, one end of the cable 20 being connected directly to the davit arm as shown at 19, and the opposite end of the cable being run over the pulley 17 and connected to a suitable drum 20 and 21. Both of these drums are journaled on suitable 25 shafts extending across the davit construction as shown in Fig. 2, one drum being arranged for the boat group to the right of the davit construction and the other drum being arranged for the boat group to the 30 left of the davit construction.

The cable 18 passes over a pulley carried by the hook block 22, which in this instance is of peculiar construction, consisting of a 35 pair of side plates 23 between which the pulley, not shown, is journaled. The lower ends of these side plates have pivoted between them a supporting hook 24 which is normally raised to the position shown in dotted lines in Fig. 7 by a spiral spring 25 carried upon a transverse pin 26 secured in the ears 27 extending laterally from the side plates. The hook 24 will be sustained in vertical position as shown in full lines in Fig. 7 when the weight of the boats or one 40 of the boats is supported thereon, but just as soon as the boat engages the water and is floated thereon, the weight will be removed from the hook and the spring will act to disconnect the same from the eye 9 and permit a quick cast-away from the side 45 of the ship without the use of a man at each end of the boat to disconnect the block. With this type of construction the men heretofore employed to disconnect the hooks 50 may be used to hold the boat away from the ship or to man the oars.

In order to raise or lower the arms 14, there are journaled in the braces 16 suitable stub shafts 28 squared at one end to receive

an operating crank 29, and having secured 60 to their opposite ends the gears 30 which engage suitable segments 31 secured to the frames 10 and 11. By rotating the shafts 65 through the cranks 29, the arms 14 may be raised or lowered, and in order to take the strain off the arms when in operating position and to reinforce the braces 15 suitable 70 chains 32 connect the outer ends of the arms 14 with the upper ends of the triangular frames 10 and 11.

Suitable lashings may be provided for holding the boats in position while being loaded or when in inactive position upon the decks of the vessel, but in order to prevent the boat from swinging toward and 75 away from the vessel while being lowered, I preferably provide a retaining device which consists of a substantially U-shaped plate 33 whose ends are bifurcated to receive the 80 rollers 34 and are also shouldered as at 85 35 to be retained within the channel-shaped track 36 which extends from the deck to the water line of the vessel.

This plate is provided with an eye 37 to 85 which is connected a turn-buckle 38 through the eye bolt 39. The opposite end of the turn-buckle has connected thereto a hook bolt 40 which engages with the hook block 22 or a portion of the lowering pin.

What is claimed is:—

1. In life saving apparatus, the combination with a plurality of nested boats, of a framework, pivotally mounted davit members carried by the framework, drums carried by the framework, cables operating 95 over said drums, hook blocks connected to the cables, means attached to each boat for engagement by the hook blocks whereby the boats may be raised and lowered independently, and means for raising and lowering 100 the davit members.

2. A life saving apparatus including a plurality of sets of nested boats, frames arranged intermediate the sets, davit members pivotally mounted on the frame and 105 acting oppositely to coöperate with a particular set, drums carried by the frames, cables coöperating with a particular drum and with a particular davit, means for operating the davits, and means carried by 110 each boat to permit the connection of the cable thereto.

In testimony whereof I affix my signature in presence of two witnesses.

CARL RYDELL.
